United States Patent Office.

WILLIAM ZIERATH AND CHARLES J. SMITH, OF SHEBOYGAN,
WISCONSIN.

Letters Patent No. 91,895, dated June 29, 1869.

IMPROVED SCRUBBING AND MOPPING-MACHINE.

The Schedule referred to in these Letters Patent and making part of the same.

To whom it may concern:

Be it known that we, WILLIAM ZIERATH and CHARLES J. SMITH, of Sheboygan, in the county of Sheboygan, and State of Wisconsin, have invented a new and useful Improvement in Automatic Scrubbers and Moppers; and we do declare that the following is a true and accurate description thereof, reference being had to the accompanying drawings, and to the letters of reference marked thereon, and being a part of this specification.

Figure 1 is a perspective view from the rear.

Figures 2 and 3 are sections.

Like letters indicate like parts in each figure.

The nature of this invention relates to an improvement in scrubbing and mopping-machines, being automatic in its operation, and consists in mounting upon a proper frame, provided with suitable brushes, water-tank, &c., surmounting proper traction-wheels, as hereinafter described.

A, in the drawings, represents a proper frame, to which are attached the traction-wheels B and B'.

Wheel B is placed upon a short axle, which is rigidly attached to the under side of frame A, so that the wheel may rotate freely upon said axle.

The shaft C, fig. 3, is journalled to the under side of the frame, to the outer end of which is rigidly fastened the traction-wheel B', while its inner end carries the bevel-gear wheel D.

The standard E is firmly secured to the frame A, so that the bevel-gear wheel F on its lower end will engage with the gear-wheel D.

Attached to the lower side of the wheel F are arms which carry the brushes G, as shown.

To the rear end of the frame A is pivoted the frame H, the lower part of which is provided with a mop-

jaw, I, to receive the sponge J, or other suitable material, the same being held in place by proper thumb-screws.

K is a spring, one end of which is attached to the frame A, while its lower end presses against the mop, to keep the same to its work.

The water-tank L is placed upon the frame A, and is provided with the outlet-pipe M, said pipe being provided with a stop-cock, N, for the purpose of regulating the flow of water.

O is a handle attached to one end of the machine, for the purpose of operating the same.

A standard, P, provided with a caster-wheel on its lower end, is attached to the rear part of the machine, for the purpose of sustaining the same.

To operate this invention, it is necessary to fill the tank L with water; then, by drawing or pushing the machine over the area to be cleaned, the brushes are caused to revolve, thus effectually doing the work as is intended.

What we claim as our invention, and desire to secure by Letters Patent, is—

1. The brushes G and the mop-jaw I, when constructed, arranged, and operating substantially as set forth.

2. In combination with the above-named parts, the frame A, gear-wheels D and F, the frame H, the water-tank L, mounted upon suitable traction-wheels, when operating substantially as and for the purposes herein set forth and shown.

WM. ZIERATH.
CHAS. J. SMITH.
